US00D790030S

(12) United States Design Patent (10) Patent No.: US D790,030 S
Ulbrich et al. (45) Date of Patent: * Jun. 20, 2017

(54) LOADER

(71) Applicants: Mason Ulbrich, Saugus, CA (US);
Kevin Schroeder, Simi Valley, CA (US); Jeff Schroeder, Simi Valley, CA (US)

(72) Inventors: Mason Ulbrich, Saugus, CA (US);
Kevin Schroeder, Simi Valley, CA (US); Jeff Schroeder, Simi Valley, CA (US)

(73) Assignee: Ulbrich Schroeder Design Corp, Simi Valley, CA (US)

() Term: 15 Years

(21) Appl. No.: 29/590,939

(22) Filed: Jan. 13, 2017

(51) LOC (10) Cl. 22-01

(52) U.S. Cl.

USPC D22/108

(58) Field of Classification Search

USPC D22/108

CPC F41A 9/83; F41A 9/82

See application file for complete search history.

(57) CLAIM

The ornamental design for a loader, as shown and described.

DESCRIPTION

FIG. 1 is a perspective view embodying the inventive design;

FIG. 2 is a top view thereof;

FIG. 3 is a right view thereof;

FIG. 4 is a bottom view thereof;

FIG. 5 is a left view thereof;

FIG. 6 is a front view thereof;

FIG. 7 is a back view thereof;

FIG. 8 is a perspective view of a second embodiment of the inventive design;

FIG. 9 is a top view of FIG. 8;

FIG. 10 is a right view of FIG. 8;

FIG. 11 is a bottom view of FIG. 8;

FIG. 12 is a left view of FIG. 8;

FIG. 13 is a front view of FIG. 8; and,

FIG. 14 is a back view of FIG. 8.

The broken lines in the figures are shown for illustrative purposes only and form no part of the claimed design.

1 Claim, 6 Drawing Sheets
